UNITED STATES PATENT OFFICE

ALFRED B. SCHUPP, OF RICHMOND HILL, NEW YORK, ASSIGNEE, BY MESNE ASSIGNMENTS, TO MOTO METER GAUGE & EQUIPMENT CORPORATION, OF LONG ISLAND CITY, NEW YORK, A CORPORATION OF DELAWARE

METHOD OF MANUFACTURING SPARK PLUGS

Application filed July 21, 1928. Serial No. 294,445.

My present invention relates to the manufacture of spark plugs and is particularly concerned with a method of manufacture whereby the production of spark plugs having gaps 5 of uniform and accurate widths will be facilitated.

It is obviously desirable in any spark plug that the electrode terminals be set apart a distance which experience has determined 10 to be best for the operating conditions for which the plug is designed. In the case of spark plugs of the motometer type which have a variable gap, it is particularly desirable that the initial gap setting be accurate, as otherwise the final gap may be too 15 large, thus causing the cylinder to miss, or if the initial gap be too small the spark will be too feeble, particularly at lower temperatures. In accordance with my present invention I propose to make the gaps narrower than the final gap desired without taking pains that such narrowed gaps are of any accurate predetermined value. I then interpose a moving, grinding surface of predetermined thickness equal preferably to the width 20 of the gap desired, thus grinding away one of the terminals the necessary amount.

The invention will be best understood by reference to the following detailed description 30 taken with the annexed drawing in which:

Figure 1 shows, in perspective, the operation of my improved method;

Figure 2 is a view in elevation seen from the 35 right of Figure 1; and

Figure 3 is a view of a grinding element employed.

In Figure 1, A denotes the spark plug having a central electrode 10 and an electrode 11 40 which is of thermostatic metal and arranged so as to produce a wider gap when the cylinder is hot.

In the manufacture of the spark plug in accordance with the present invention, the 45 gap is set at some value smaller than the desired one but without any attempt at precision being made. A grinding element, forming part of a grinding mechanism denoted generally by B, is thereafter interposed and 50 operated between said electrodes with the re-

sult that the material of the electrode next to the grinding surface of the disk is quickly ground away and a gap of the desired size is produced.

As indicated, grinding element B consists 55 of a rotatable spindle 12 carrying a disk 13 having one surface thereof formed of abrasive material of suitable type. Disk 13 is removably held on said spindle by means of a holding screw 14, it being noted that disk 13 has an aperture 15 of non-circular shape which fits the end of the spindle 12 of corresponding shape. Preferably the width of said disk 13 is substantially that of the desired width of gap so that the grinding element may be 60 interposed between the electrodes and quickly withdrawn, whereupon the correct gap will be formed automatically. As shown, the disk 13 is preferably covered with the abrasive material on one side only, the other side being 65 smooth, although if desired both sides may be so covered. However, it is usually desirable to have the grinding take place on the electrode other than the central electrode as the size of the latter is necessarily limited, and therefore the use of a disk having abrasive on one side only is preferred.

In this manner, an easy, quick, and accurate method is provided for insuring that the 70 spark plugs are manufactured of uniform spark gap. At the same time the need for precision in manufacture and in assembly of the parts is substantially reduced so that rejections of parts are less frequent, and production is speeded.

The grinding of the gap has the further 75 advantage that the sparking surfaces are made clean and bright.

Various changes may be made from the 80 method above described in detail without departing from the spirit of the invention.

I claim:

1. In the manufacture of spark plugs, the 85 method of forming a gap of uniform width between the electrode terminals which consists in originally forming the gap of less width than that desired, providing a rotary grinding element equal in thickness to the final width of gap desired, and operating said 90 100

element between the electrodes to cut the gap to the desired width.

2. The method according to claim 1, in which the grinding is confined substantially to one of the electrodes.

5 3. The method according to claim 1, in which the grinding is confined substantially to the non-central electrode.

10 In testimony whereof I have affixed my signature to this specification.

ALF. B. SCHUPP.
